UNITED STATES PATENT OFFICE.

THOMAS G. COOK, OF PHILADELPHIA, PENNSYLVANIA.

DESIGN FOR DRINKING-GLASSES, &c.

Specification forming part of Design No. **6,987**, dated November 11, 1873; application filed March 7, 1873.
[Term of Patent 7 years]

To all whom it may concern:

Be it known that I, THOS. G. COOK, of Philadelphia, in the county of Philadelphia and State of Pennsylvania, have invented a certain new and useful Design for Glasses, Tumblers, &c.; and I do hereby declare the following to be a full, clear, and exact description of the same, reference being had to the accompanying drawings, which form part of this specification:

This design consists in the configuration for keystone, plain or starred, applied to a drinking-glass.

The design may be formed upon the bottom

of the glass, as shown at B in Fig. 1, upon the side, as shown at A in Fig. 3, or upon the face of a shield, as shown in Figs. 2 and 3 at C.

What I claim as my design is—

The configuration of a keystone, plain or starred, upon a drinking-glass, as shown and described.

In testimony that I claim the foregoing I have hereunto set my hand.

THOMAS G. COOK.
